2,276,044

MINERAL CONCENTRATOR

Arthur Alvah Johnston, Spokane, Wash.

Application July 10, 1939, Serial No. 283,701

3 Claims. (Cl. 209—44)

The device which forms the subject-matter of this application, embodies a novel means for classifying and separating material, for example, crushed ore, novel means being supplied for segregating the heavier portions of the ore from the lighter portions thereof, and novel means being provided for imparting movement to a frame, carrying a classifier and concentrators, in such a way that a proper separation between the heavier and lighter portions of the material will be consummated, novel means being supplied for rotating the frame and associated parts to produce, in the concentrators, places of restricted area where the heavier portions of the material will settle.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in side elevation, a device constructed in accordance with the invention;

Fig. 2 is a vertical section taken on the line 2—2 of Fig. 1, the lower bearing being in a vertical position;

Fig. 3 is a horizontal section on the line 3—3 of Fig. 2;

Figs. 4 and 5 are plans showing parts carried by the movable frame;

Fig. 6 is a plan showing another of the parts carried by the movable frame;

Fig. 7 is a perspective of the frame;

Fig. 8 is a bottom plan showing the crank arm and attendant parts.

In the drawings there is shown a support 1, which may be constructed as desired. On the bottom of the support 1 is mounted a guide 2 wherein a slide 3 is mounted for right-line adjustment, the slide carrying a bearing socket 4. The numeral 5 marks a head secured to the top of the support 1, and in the head, a vertical driven shaft 6 is supported for rotation by any appropriate means, such as a drive shaft 7 journaled in the head and operated by a crank or otherwise, the shafts 6 and 7 being operatively

connected by bevel gears 8. A crank arm 9 is secured to the lower end of the shaft 6 and is provided, near its end, with an opening 10.

The numeral 11 marks a frame, mounted for rotation and for rocking movement on the support 1, the frame including a loop-shaped body 12, provided at its upper end with a stub shaft 14, received in the opening 10 of the crank arm 9 on the shaft 6. At its lower end, the body 12 of the frame 11 is supplied with a spindle 15, received in the bearing 4 on the adjustable slide 3.

A horizontal U-shaped brace 16 has its ends secured to the body 12 of the frame 11. An outstanding angle bracket 17 is secured to the intermediate portion of the brace 16 and to the intermediate portion of the bottom of the body 12 of the frame 11. There are vertically spaced openings 18 in the vertical arm of the bracket 17. At its upper end, the vertical arm of the bracket 17 is provided with an opening 20. There are vertically spaced seats 19 in the side arms of the body 12 of the frame 11. The inner end of a lateral arm 21 is secured to the intermediate portion of the top member of the body 12 of the frame 11, and is provided, near its outer end, with an opening 22.

One end of a link 23 is pivotally mounted in the opening 20 of the frame bracket 17, the opposite end of the link being pivotally mounted in one end of a cross arm 24, secured to the support 1. The upper end of a pull spring 25 is connected to the link 23, near the cross arm 24, and the lower end of the spring is connected to the support 1. If desired, the link 23 can be shifted 35 over into pivotal mounting in the opening 22 in the arm 21 on the frame 11 and in a corresponding opening 27 in the cross piece 24.

The numeral 28 designates an upper classifier, in the form of a pan, and having an outlet spout 29 at its periphery. The bottom of the upper classifier 28 is perforated as shown at 30. The numeral 31 marks a lower classifier, having an outlet spout 32. The bottom of the lower classifier 31 is provided with perforations 33. An upwardly convexed baffle 34 is located below the bottom of the lower classifier 31 and is secured to the bottom, centrally thereof. The numeral 34 marks a perforated depression in the bottom of the lower classifier 31.

At 35 there appears an upper concentrator which is a pan-like form. The upper concentrator 35 has a depression 36 in its bottom, and across the depression extends a screen 38. A drain pipe 39 is connected to the central portion of the depressed part 36. The bottom of the

upper concentrator 35 is imperforate, saving for a central opening 40, surrounded by an upstanding sleeve 41 having an outstanding flange 42.

A lower concentrator 43 is provided, and is of pan-like form and has a depression 44. The bottom of the lower concentrator 43 is imperforate. On the bottom of the lower concentrator 43 there is an upstanding sleeve 45 located below the baffle 49 and provided with an inwardly extended and downwardly inclined annular flange 46 having a central opening. A drain pipe 47 is formed in the bottom of the lower concentrator 43 and communicates with the sleeve 45. A central standard 48 is secured to the bottom of the lower concentrator 43, and carries a circular, upwardly convexed baffle 49 located above the sleeve 45.

The upper classifier 28, the lower classifier 31, and the upper concentrator 35 are provided on their bottoms with fixed rods 50, the ends of which project beyond the peripheries of the parts mentioned. The upper classifier 28, the lower classifier 31, and the upper concentrator 35 are supplied with projections 51, disposed at right angles to the rods 50. The ends of the rods 50 are received detachably in the seats 19 of the side arms of the body 12 of the frame 11. The projections 51 are received in the openings 18 in the vertical part of the bracket 17.

The lower concentrator 43 is supported from the lower part of the body 12 of the frame 11, and has a peripheral U-shaped holder 52, adapted to straddle the vertical arm of the bracket 17, below a transverse keeper 53 on the vertical part of the bracket 17.

In practical operation, rotation is imparted to the driven shaft 6 by means of the drive shaft 7 and its crank, or an equivalent, and through the instrumentality of the intermeshing beveled gears 8. When the shaft 6 is rotated, the crank arm 9 causes the stub shaft 14 of the frame 11 to move in an orbit, the center of which is the lower bearing 4 of Fig. 2. That bearing, however, may be adjusted inwardly or outwardly from the neutral position shown in Fig. 2, through the instrumentality of the slide 3. The link 23 and associated part prevent the frame 11 from rotating about an axis represented by the stub shaft 14 and the finger 15 of Fig. 7, but, as hereinbefore stated, the stub shaft 14 moves in an orbit, and the position of the bearing 4, which receives the spindle 15 of the frame 12, may be adjusted in or out as desired.

Large, heavy portions collect and remain in the classifier 28, and the tailings discharge. All small portions and water pass through the perforations 30 and are received by the classifier 31, which functions in a manner similar to the classifier 38, but with a spot assembly. The small portions and water pass to the concentrator 35, where spot assembly retains the heavier portions, water and slimes being discharged through the sleeve or outlet 41, to be received, by the concentrator 43, which operates in a similar manner.

It has been found, however, that in the operation of the device, places exist where the heavier portions of the ore are brought together, those places being the depression 34 of the lower classifier 31 and the depression 36 of the upper concentrator 35.

The upwardly convexed baffle 54 on the bottom of the lower classifier 31 prevents the water from the flowing into the sleeve 41 of the upper concentrator 35. The water and ore pass into

the upper concentrator 35, the heavier portions collecting in the depression 36, the concentrate being drained from that depression by the pipe 39.

5 The baffle 49 prevents the water from entering the sleeve 45 of the lower concentrator 43, the material being received in the lower concentrator, and the heavier portions of the material collecting in the depression 44. Although, in its 10 downward flow, the water from the upper concentrator 35 is not received directly in the sleeve 45 of the lower concentrator 43, when motion is imparted to the frame 11 and associated parts the water and slimes gradually will find their 15 way into the sleeve 45, over the flange 46, and leave by the pipe 47.

Especial attention is directed to the fact that the heavier portions of the ore tend to collect in the neutral points represented by the various depressions, such as the depressions 34, 36 and 44, a gradual dispersing of the tailings taking place through the spouts, such as the spouts 29 and 32.

Especial attention is directed to the compound movement imparted to the frame 11 and parts carried thereby. The stub shaft 14 has orbital movement about an axis represented by the lower bearing 4, the position of that axis can be changed by shifting the slide 3 in or out, and rotation of the frame 11 is prevented by the pivoted link 23.

The device is simple in construction, but will be found thoroughly advantageous for the ends in view.

What is claimed is:

35 1. In a device of the class described, a support, a frame, a mineral-receiving mechanism carried by the frame and embodying upper and lower pan-like members, each of said members having a collecting depression offset with respect to said axis, the bottom of the upper of said members having central outlet means discharging into the lower of said members, a bearing wherewith the lower end of the frame is engaged: means on the support for moving the upper end of the frame orbitally about an axis determined by the position of the bearing, and means for restraining the frame against rotation, all of said means cooperating to produce spot-assembly in the heavier portions of the mineral in said mechanism.

50 2. In a device of the class described, a support, a frame, mineral-receiving mechanism carried by the frame and comprising upper, lower and intermediate pan-like members, the upper of said members having a lateral discharge for tailings, each of said members having a collecting depression offset with respect to said axis, the upper member being perforated for discharge into the intermediate member, the intermediate member having a central upstanding sleeve leading to the lower member, the lower member having a central upstanding discharge sleeve, a baffle secured above each sleeve, a bearing wherewith the lower end of the frame is engaged: means on the support for moving the upper end of the frame orbitally about an axis determined by the position of the bearing, and means for restraining the frame against rotation.

70 3. In a device of the class described, a support, a frame, mineral-receiving mechanism carried by the frame and comprising upper, lower and intermediate pan-like members, each of said members having a collecting depression offset with respect to said axis, the upper member being perforated for discharge into the intermediate mem-

ber, the intermediate member having a central upstanding sleeve leading to the lower member, the lower member having a central upstanding discharge sleeve, a baffle secured above each sleeve, a bearing wherewith the lower end of the frame is engaged: means on the support for moving the upper end of the frame orbitally about an axis determined by the position of the

bearing, means on the support for shifting the bearing, thereby to change the position of said axis at the will of an operator, and means for restraining the frame against rotation, all of said means cooperating to produce spot assembly in the heavier portions of the mineral in said mechanism.
